DESIGN FOR A SHOE SOLE

Maurice J. Bernstein, Brighton, Mass., assignor to Panther-Panco Rubber Co. Inc., Chelsea,
Mass., a corporation of Massachusetts

Application March 7, 1939, Serial No. 83,392

Term of patent 14 years

To all whom it may concern:

Be it known that I, Maurice J. Bernstein, a citizen of the United States, residing at Brighton, in the county of Suffolk and Commonwealth of Massachusetts, have invented a new, original, and ornamental Design for a Shoe Sole, of which the following is a specification, reference being had to the accompanying drawing, forming part thereof.

In the drawing Fig. 1 represents a plan view of a shoe sole showing my new design; and Fig. 2 is a longitudinal section taken on the line 2—2 of Fig. 1.

I claim:

The ornamental design for a shoe sole, substantially as shown.

MAURICE J. BERNSTEIN.
